UNITED STATES PATENT OFFICE.

ADOLPHE LE MOULT, OF NEW YORK, N. Y.

DESIGN FOR A FLOWER-PIECE.

SPECIFICATION forming part of Design No. 17,875, dated November 8, 1887.

Application filed October 1, 1887. Serial No. 251,947. Term of patent 7 years.

To all whom it may concern:

Be it known that I, ADOLPHE LE MOULT, of the city, county, and State of New York, have invented a certain new and original Design for a Flower-Piece, of which the following is a specification, reference being had to the accompanying drawing, which fully illustrates the nature of my design.

This invention relates to a design for a flower-piece for funeral purposes; and it consists of a pillow-shaped body having intertwining links on the body, the outermost link being broken, said links being provided with bows, a bouquet of flowers being arranged in one of the upper corners of the pillow.

A represents a pillow-shaped ground or body of the flowers; B B, a number of intertwining links that are provided with bows C, respectively at opposite sides of the same. The links extend from one side of the pillow

toward the opposite corner of the same, the last link being broken. At one of the upper corners a bouquet, D, tied by a ribbon, is arranged.

Having thus described my design, I claim as new and desire to secure by Letters Patent—

A design for a flower-piece, composed of a pillow-shaped body or ground, intertwining links and bows on said ground, the last link being broken, and a bouquet tied by a ribbon in one of the corners of the body, substantially as shown and described.

In testimony that I claim the foregoing as my invention I have signed my name in presence of two subscribing witnesses.

ADOLPHE LE MOULT.

Witnesses,

SIDNEY MANN,
MARTIN PETRY.
